(57) **CLAIM**

The ornamental design for an activity bib, as shown and described.

DESCRIPTION

FIG. 1 is a perspective view of the activity bib of the present invention; and

FIG. 2 is a front view thereof;

FIG. 3 is a left side view thereof;

FIG. 4 is a right side view thereof;

FIG. 5 is a top end view thereof; and,

FIG. 6 is bottom end view thereof.

The broken lines in the drawings are for the purpose of illustrating environmental structure which form no part of the claimed design.
